VILHELM IRGENS PETTERSSON, OF GOTTFENBORG, SWEDEN.

MACHINE FOR GATHERING SHEAVES IN THE FORM OF CYLINDRICAL HOLLOW BUNDLES FROM MOWED GRASSES, CEREALS, OR THE LIKE.

Application filed August 20, 1924, Serial No. 733,292, and in Germany August 29, 1923.

The invention relates to a machine for forming cylindrical hollow bundles from mowed grasses, cereals or the like.

Instead of, as hitherto, laying aside or binding the cut cereal in sheaves, the new machine piles the goods together in cylindrical, cone shaped or similarly formed hollow bodies, hereinafter referred to as "bundles" or "grain cylinders" and ejects them in 10 this form, which they retain by reason of a twisting and compressing action imparted thereto. The bundles so formed are more readily dried than ordinary sheaves, which is a great advantage when the harvesting 15 takes place in wet weather.

In the drawings a constructional embodiment is shown, by way of example, of one form serving as a right-hand cutting machine according to the invention.

20 Figure 1 shows a longitudinal section of the machine taken substantially on line I—I of Fig. 2; Fig. 2 a horizontal sectional plan of the platform, taken substantially on line II—II of Fig. 1, parts being omitted for the 25 sake of clearness; Fig. 3 a side view of the same platform; Fig. 4 a vertical section on the line IV—IV of Fig. 1; Fig. 5 a side view of the machine from the left; Fig. 6 a modified construction of platform in plan view; 30 Fig. 7 a side view corresponding to Fig. 6; Fig. 8 a second modified form of the platform in side view; Fig. 9 a plan view of a portion of the platform shown in Fig. 8.

The cylinder 2 is concentric with and connected to the outer running wheel 1. On the inside of the outer running wheel is a toothed rim 3 fitted with small grooves 3'. In these small grooves 3' at for example three points, adjustable arms 5 of the frame 40 6 of the machine engage by the medium of the rollers 4; in this frame is secured the shaft or beam 7. The outer running wheel 1 can rotate about the rollers 4 of the frame 6, and on drawing the machine along by pulling 45 the shaft rolls on the ground. The axle 8 of the inner cylinder 9 is arranged concentric with cylinder 2 and rotatable in frame 6. Between the outer cylinder 2 and the inner cylinder 9 is a hollow space 10 across the 50 entire width of the running wheel, in which the grasses and cereals are brought, fastened together and formed into a cylindrical bundle. At the side, the frame 6 is provided with a support 11, which is carried at its 55 outer end by the carriage wheel 13 and car-

ries in front a cutting device 12 of known design. Between the cutting device and the support 11, are arranged transporting webs, for example 14, 15, of cloth or the like, these having the object of taking the reaped crop 60 and conveying it to the annular cylindrical hollow space between the parts 2 and 9, which can be accomplished in various ways. The webs may be said to constitute a platform on to which the crops fall as they are 65 cut by the device 12.

One form is shown in front view, plan and side view in Figs. 1, 2, and 3 respectively. The reaped crop is conveyed from the cutting device 12 by a special endless web 15 to 70 the main endless web 14 provided with studs 60 to aid the transportation and working transversely to the driving direction of the machine.

75 Since the cut straws are moved with their ears foremost, by the web 15 in opposition to the driving direction of the machine, and by the endless web 14 transverse to the driving direction, a turning of the corn and a forwarding of the ears towards the hollow 80 cylinder is effected. On the side away from the cutting device, the web 14 is bounded by a further endless upright web 16, which itself moves as quick or quicker than the web 14. The tray-like slide 17, whose shape 85 changes gradually from the flat of the surface of the horizontal transporting web 14 to the curvature of the hollow cylinder, guides the cut products from the platform to the hollow cylinder. In the cylindrical 90 hollow space 10 move the longitudinally movable rams 18 (Figs. 1 and 4) connected together more or less in dovetailed manner. These are guided by means of the suitably formed arms 19, on a curved rail 20 fixed 95 to the frame 6 in such a way that at the delivery point of the tray-shaped slide 17 they are entirely withdrawn from the annular space, yet they are completely pushed into the said cylindrical space at the diametrically opposite point. Upon rotation of the working cylinder the rams 18 are carried along therewith either by natural rubbing 100 or in any convenient manner. It is therefore evident that the reaped crops which are 105 conveyed to the hollow space from the platform over the tray 17 are gradually compressed by the rams and pushed forward. The reaped crops in this way strike against the cogs of the wheels 21, projecting through 110

the inner cylinder 9 into the hollow space 10, two or more of which wheels are arranged radially to the hollow cylinder. The cogs of the wheels 21 engage with the endless screw 22, which is rotatably mounted on the axle 8, but can be coupled thereto by the couplings 23. At the beginning of the work the two wheels 21 and the at present uncoupled screw 22, stand still relative to the self-rotating cylinder; with increased feeding of the reaped crops and increased pressure the wheels 21 are turned by the grain cylinder in the direction of the arrows a , the endless screw 22 is displaced along the axle 8 towards the left and coupled thereto through the coupling 23. The endless screw 22 hereby receives the same speed of revolution as the axle 8. This is such that now the wheels 21 receive a rotation opposite to the direction of arrows a , and with their cogs retard the forward movement of the cylinder of grain in the hollow cylinder in the direction of arrows b . The rotating motion of the axle 8 is derived, as shown in Figs. 1 and 2, through the change wheels 24, 25, the spur wheels 26, 27, the worm wheels 28, 29, the pair of spur wheels 30, 31, and the pair of bevel wheels 32, 33 from shaft 35 which is coupled and uncoupled by means of the coupling 34 and driven by cog wheel 36 mounted thereon from the toothed rim 3 of the track wheel 1. By varying the wheels of the change gear 24, 25, a change in speed of the endless screw 22 and hence of the cog wheels 21 is obtained, so that it is possible to adjust the forward velocity of the cylinder of grain according to the strength and quality of the straw, and its degree of dampness in any given working conditions.

The inner cylinder 9 extends beyond the topmost ram 18 a distance y which is approximately equal to the desired length of the finished bundle, referred to as the "grain cylinder". The outer cylinder 2 projects beyond the inner cylinder 9 a further distance x which is slightly greater than the distance y , and is cut away to provide an ejection aperture 53. A cylindrical sleeve 37 is rotatably mounted upon the outer end of the cylinder 2 and has an aperture 52 therein, which from time to time comes into registration with the aperture 53 to allow the grain cylinders to be discharged from the machine as they are completed. The sleeve 37 will rotate together with cylinder 2 by reason of the friction therebetween, but its rotation is adapted to be arrested by a projection 42 thereon coming against arm 41 of a vertical spindle 40 journaled in the frame 39 which is rigidly secured to frame 6 of the machine. The arm 41 is normally held by means of a spring 45 in a position out of the path of abutment 42 so that the sleeve 37 is free to rotate. A roller 38 is

carried by an arm secured to the upper end of spindle 40, and projects somewhat within the cylinder 2 and in line with the annular space 10. This arrangement results in that as the grain cylinder formed in space 10 is advanced into the discharge end of cylinder 2, it presses against the buffer roller 38, turns the spindle 40 against the action of spring 45, thereby moves the arm 41 into the path of abutment 42 so that the sleeve 37 is arrested with its aperture 52 directed downwards and rearwards, and as aperture 53 in cylinder 2 comes into registration, a grain cylinder of length x will fall by its own weight out on to the field, as herein-after explained. Actuation of the buffer roller 38 also interrupts the feed of the conveyer mechanism by disengaging the coupling 34 by means of draw-bar 44 pivoted to a crank arm 43 secured upon the lower end of spindle 40.

The division of one grain cylinder from the following one is effected according to the preferred method in this way. In operation the machine is first worked until a cylinder of grain is formed extending from the rams 18 to the buffer roller 38, pushing back the latter and thus causing the clutch 34 to be disengaged and interrupt the advance of fresh material to the annular space 10, and at the same time arresting the sleeve 37 as above described so that the aperture 53 comes into registration with the aperture 52. This long grain cylinder is then cut into two approximately at the position indicated by arrows z , by hand or in any other convenient manner and the portion thus severed will fall out. Now during the time that one grain cylinder is undergoing ejection, which corresponds approximately to one revolution of the cylinder 2, the rams 18 act upon the rear end of the following grain cylinder to compress same without additional material being added. So, when the buffer roller 38 is allowed to be brought back by its spring 45 into the normal position incidentally the sleeve 37 is released, the coupling 34 re-engaged, more material is fed forward to the rams by the conveyor, and the formation of another grain cylinder is commenced. Thus, by interrupting the conveyor mechanism a division is made between consecutive grain cylinders which suffices to enable said cylinders to fall out, one by one, as they reach the ends of cylinder 2 and cause the exit apertures 52, 53 to come into appropriate registering position.

The separation of the first formed grain cylinder by cutting as described above might in some cases be effected alternatively by operating the buffer roller mechanism manually when a grain cylinder of length x is first formed.

The treatment which the stalks receive

within the annular space 2 enables the finished bundles to retain their shape without additional binding means as is necessary for ordinary sheaves. The bundles will lie on the ground on their sides until stood on end manually or otherwise when they will dry much more readily than ordinary sheaves by reason of their form, particularly if raised somewhat on one side so that 10 a through passage for air is provided.

It is obvious that the machine above described admits of various modifications without departing from the scope or spirit of the invention. For example the platform 15 can also be constructed according to Figs. 6 and 7, where two endless webs work behind each other in the same direction; the web 46 moves quicker than web 47, so that here also the stalks are turned and conveyed 20 in the proper direction to the tray and so to the hollow cylinder.

In Figs. 8 and 9 a further embodiment of the platform is shown. There are two endless webs 48 and 49 disposed one over the 25 other between which the reaped crops are taken and conveyed to the slide and so to the hollow cylinder. The cut goods fall first on the upper web 48 which carries them outwardly. At 50 an interchangeable plate 30 51 of dimensions according to the length of the grain is disposed between the cut stalks and the smaller endless web 49. The eared ends of the stalks are seized while the straw ends fall on the polished sheet 51. Here 35 also the forwarding of the eared ends as against the straw ends is effected and the reaped crops are conveyed in appropriate position between the webs to the slide and so to the hollow cylinder.

40 The machine can be adapted for driving through narrow and small ways in known manner by means of displaceable wheels and for driving longitudinally and also so constructed that the platform can be closed up.

45 I claim:

1. In a reaping machine, means for forming the cut-crops into bodies of substantially hollow cylindrical form, comprising an inner cylinder and a concentric outer cylinder, 50 means for feeding the cut-crops to the annular space between said cylinders, means for rotating cut-crops in the annular space with respect to the cut-crops being fed thereto, means for compressing the cut-crops in said annular space, means for interrupting the feeding of said crops to the annular space, and means for releasing from the machine the hollow body so formed during interruption of said feeding.

60 2. In a reaping machine, means for forming the cut-crops into bodies of substantially hollow cylindrical form comprising an inner cylinder and a concentric outer cylinder, including a plurality of endless transporting 65 webs moving at different speeds, means for

feeding the cut-crops to the annular space between said cylinders, means for rotating cut-crops in the annular space with respect to the cut-crops being fed thereto, means for compressing the cut-crops in said annular space, means for interrupting the feeding of said crops to the annular space, and means for releasing from the machine the hollow body so formed during interruption of said feeding. 70

3. In a reaping machine, means for forming the cut-crops into bodies of substantially hollow cylindrical form comprising an inner cylinder and a concentric outer cylinder, including a plurality of endless transporting webs moving at different speeds, means for feeding the cut-crops to the annular space between said cylinders, means for rotating cut-crops in the annular space with respect to the cut-crops being fed thereto, 80 means for compressing the cut-crops in said annular space comprising rams and means for imparting reciprocating movement thereto, means for interrupting the feeding of said crops to the annular space, and means for releasing from the machine the hollow body so formed during interruption of said feeding. 85

4. In a reaping machine, means for forming the cut-crops into bodies of substantially hollow cylindrical form, comprising an inner cylinder and a concentric outer cylinder, including a plurality of endless transporting webs moving at different speeds, means for feeding the cut-crops to the annular space between said cylinders, means for rotating cut-crops in the annular space with respect to the cut-crops being fed thereto, means for compressing the cut-crops in said annular space comprising rams, means for reciprocating said rams in said annular space and a device for controlling the advance of the compressed crops through said annular space, means for interrupting the feeding of said crops to the annular space, and means for releasing from the machine the hollow body so formed during interruption of said feeding. 95 100

5. In a reaping machine, means for forming the cut-crops into bodies of substantially hollow cylindrical form, comprising an inner cylinder and a concentric outer cylinder, means for feeding the cut-crops to the annular space between said cylinders, means for rotating cut-crops in the annular space with respect to the cut-crops being fed thereto, means for compressing the cut-crops in said annular space, a buffer roller in the path of the compressed crops and controlling the feeding means and the exit of the outer cylinder, substantially as and for the purpose stated. 115 120

6. In a reaping machine, means for forming the cut-crops into bodies of substantially hollow cylindrical form, comprising an inner 130

1 cylinder and a concentric outer cylinder, arranged concentrically within a running wheel of the machine said outer cylinder being firmly connected with said running wheel, rams slidable in the hollow annular space between the two cylinders, means for feeding the cut-crops to said annular space, means for compressing the crops in said annular space comprising a device for withdrawing said rams from said annular space

15 at the part where the cut-crops enter same and for driving said rams into said annular space at the diametrically opposite part thereof, and means for automatically interrupting the feeding means when a predetermined quantity of compressed crops fill the annular space and for simultaneously releasing said compressed crops.

VILHELM IRGENS PETTERSSON.
